UNITED STATES PATENT OFFICE.

NEVA I. MILLS, OF LOS ANGELES, CALIFORNIA.

BASSINET.

Application filed October 31, 1921. Serial No. 511,550.

To all whom it may concern:

Be it known that I, NEVA I. MILLS, a citizen of the United States, residing at Los Angeles, in the county of Los Angeles and 5 State of California, have invented new and useful Improvements in Bassinets, of which the following is a specification.

My invention relates to bassinets, and the purpose of my invention is the provision of 10 a bassinet of extremely simple and efficient construction which is particularly designed for the carrying of infants, the invention including yokes which are movable to provide a handle for carrying the bassinet, and 15 means for locking the yokes in such position.

My invention also provides a bassinet having a hood or canopy for protecting the occupant against the elements, and means for locking the hood in extended position.

20 I will describe one form of bassinet embodying my invention and will then point out the novel features thereof in claim.

In the accompanying drawings,

Figure 1 is a view showing in side elevation one form of bassinet embodying my invention.

Fig. 2 is a top plan view of the bassinet shown in Fig. 1.

Fig. 3 is an enlarged fragmentary perspective view showing the handle portion of one of the yokes.

Figs. 4 and 5 are enlarged fragmentary views showing in side and end elevation, respectively, the locking means for the hood.

35 Fig. 6 is a transverse sectional view of the handle shown in Fig. 3.

Similar reference characters refer to similar parts in each of the several views.

Referring specifically to the drawings, my 40 invention, in its present embodiment, comprises a body portion designated at B and which is of the usual bassinet contour. In the present instance the body B is formed of a skeleton frame work including longitudinally extending rods 15 which are bent at their ends upwardly to a common point where they are secured by a spot welding to the curved ends of a frame 16. This frame is of elongated form and with rounded ends. Transversely arranged arcuately bent brace rods 17 are also provided which are arranged in intersecting relation to the rods 15. The ends of the rods 17 are looped to engage the side portions of the frame 16 and to thereby form an efficient brace for the interior body.

To render the body ornamental as well as useful, it can be covered with any suitable material, such as cloth, or wickerwork, it being understood that the material is secured in spanning relation to the rods and frame. 60

Swingingly supported upon the side portions of the frame 16 at points between the rods 17 are yokes 18 of substantially U-shaped formation with their ends looped 65 about the frame as shown. The intermediate portions of the yokes 18 are bent outwardly as indicated at 19, and one of these portions carries a handle 20 which, as illustrated to advantage in Fig. 3, is provided with a longitudinally extending groove 21. This

groove is designed for the purpose of receiving the other bent portion 19 of the other yoke 18 as shown in Fig. 6. The handle 20 is rotatably mounted upon the portion 19 so 70

as to effect a displacement of the groove 21 to effect a locking of the corresponding portion 19 within the handle. This is effected by a partial rotation of the handle so as to 75

displace the groove 21 in the manner indicated in dotted lines in Fig. 6. When the handle is so rotated, the portion 19 is displaced to just the extent that the corresponding yoke is held under tension whereby the two yokes can be locked in supporting position as shown in dash lines in Fig. 2. 80

When the carrier grasps the handle 20 when the yokes are arranged in this position, it will be clear that an efficient supporting means is provided for the bassinet so that 85 it can be readily carried. 90

To protect the occupant of the bassinet from the elements, a hood 22 is provided which is constructed so that it may be collapsed as shown in Fig. 1, or extended so as 95

to provide a protecting covering for the head of the infant. This hood includes a frame 23 which is of U form and looped at its ends to engage pins 24 mounted in U-shaped plates 25 arranged in embracing position 100

with respect to the side portions of the frame 16. This construction is clearly shown in Figs. 4 and 5, wherein it will be seen that the upper ends of the plates are bent inwardly as indicated at 26 to provide gripping fingers which are adapted to clamping 105

engaging the end portions of the frame 23 and to thereby secure the frame in vertical position. This obviously retains the hood in extended position. 110

Although I have herein shown and described only one form of bassinet embodying

my invention, it is to be understood that various changes and modifications may be made herein without departing from the spirit of the invention and the spirit and scope of the appended claim.

What I claim is:

A bassinet comprising a skeleton body including a frame of elongated form having rounded ends, rods extending longitudinally 10 at spaced intervals transversely with re-

spect to the frame, said rods having their ends curved upwardly and connected at a common point to the frame, brace rods engaging the first rods and secured to said frame, and yokes swingingly supported on 15 said frame between the brace rods.

In testimony whereof I have signed my name to this specification.

NEVA I. MILLS.
